UNITED STATES PATENT OFFICE.

GEORGE B. WILLIAMS, OF PITTSBURGH, PENNSYLVANIA.

DRAFTSMAN'S DEVICE.

1,094,041.

Specification of Letters Patent. Patented Apr. 21, 1914.

Application filed October 5, 1911. Serial No. 653,041.

To all whom it may concern:

Be it known that I, GEORGE B. WILLIAMS, a citizen of the United States, residing at Pittsburgh, in the county of Allegheny and 5 State of Pennsylvania, have invented a new and useful Improvement in Draftsmen's Devices, of which the following is a specification.

My invention relates to improvements in 10 platting devices for draftsmen.

The object of my invention is to produce a universal platting device in which simplicity of construction, efficiency and a minimum of cost is attained; I accomplish this 15 object by means of a device hereinafter more specifically described, reference being had to the accompanying drawings forming part hereof, in which—

Figure 1 is a plan view of my improved 20 device applied to a drawing board. Fig. 2 is an inverted plan view of the same detached from the board. Figs. 3 and 4 are details of construction.

Referring to said drawings, 1 is a draftsman's board of the usual construction, the 25 one side thereof having applied thereto, longitudinally thereof, the guide rod 2, to which is slidably connected a ruler or straight edge 3, which is adapted to swing 30 upon the pin 4 secured in the block 5, which is slidably mounted upon said guide rod.

6 is a bracket to which is pivotally connected the segmental protractor 7 and the graduated scale ruler 8, the said bracket being 35 slidably mounted on the straight edge 3

and adapted to be secured thereto by the thumb screw 9, and having one end thereof in the vernier 10. The graduated ruler is removably secured in its frame 11 by means of the fastening device which comprises the 40 hook 12 and slot block 13, in which pins on the ruler engage, being held in the slot by the hook as shown in Fig. 3. The straight edge is capable of being swung to any desired angle by means of the worm 14, which 45 meshes with the gear 15 secured to the pin 4.

One of the novel features of my device is that the protractor is provided with a degree scale from zero at the center thereof to 90° on either end in either direction. 50

Having described my invention, what I claim and desire is to secure Letters Patent:

In a draftsman's platting device, the combination of a straight edge, a slide mounted upon the straight edge and projecting upon opposite sides thereof, a protractor pivotally mounted upon one of the projecting ends of the slide, a vernier arranged upon the opposite projecting end of the slide and disposed in co-operative relation to the protractor, and a ruler carried by and projecting from the protractor. 55 60

In testimony whereof, I have hereunto signed my name in the presence of two subscribing witnesses.

GEORGE B. WILLIAMS.

In the presence of—

CLARENCE A. WILLIAMS,
JOHN H. RONEY.
